UNITED STATES PATENT OFFICE.

ABRAHAM LIEBEN, OF NEW YORK, N. Y.

BATHING-SHOE.

1,319,680.

Specification of Letters Patent.

Patented Oct. 21, 1919.

Application filed November 30, 1917, Serial No. 204,555. Renewed August 26, 1919. Serial No. 320,049.

To all whom it may concern:

Be it known that I, ABRAHAM LIEBEN, a citizen of the United States, residing at New York, county of New York, and State of New York, have invented a new and useful Bathing-Shoe, of which the following is a specification.

The object of my invention is to provide an improved bathing shoe which can be made at small expense.

Figure 1 is a perspective of my invention; Fig. 2 is a section on line 2—2 of Fig. 1; and

Fig. 3 is a detail of the blank which forms the sole.

Like numerals designate like parts in each of the views.

Referring to the accompanying drawings, my shoe has two strips of fabric 1, which are sewed together on a vertical line extending upward from the heel. These strips form the upper of the shoe. A reinforcing strip 8 conceals the seam. The fabric uppers are sewed to a fabric sole 9. I further provide a leather sole 2 formed from a single blank of sufficient size to conceal the seam between the fabric upper 1 and the fabric sole 9. The rear portion of this blank has a V-shaped cut out portion 5. The sides of the blank are curved inwardly at 4 to conform to the shape of the instep, and the sides are also inwardly curved at 10 to conform to the narrowed portion of the shoe near the toe, and the toe end of the blank has an approximately V-shaped cut out portion, the sides 3 of which, however, are curved as shown.

This form of blank can be readily sewed to the shoe. The edges 3 at the toe end and the edges 5 at the heel meet, and the opposing edges in each instance require but a single line of stitching to provide a leather sole of correct shape. This sole is sewed to the fabric upper 1, as shown in Fig. 1. The portions 2, 6, 7, and 8 are of leather, the rest 45 of the shoe being of fabric.

What I claim is:

1. A fabric bathing shoe consisting of a fabric upper, a fabric sole, a light and flexible leather sole formed from a single blank 50 of sufficient size to conceal the seam between the fabric upper and the fabric sole, the aforesaid blank having approximately V-shaped cut out portions at the heel and toe, the edges of which meet, a single line of 55 stitching extending upwardly over the toe and a single line of stitching extending upwardly over the heel securing the edges of the cut-out portions above described, and a single line of stitching securing the upper 60 edge of the sole blank to the fabric upper.

2. In a bathing shoe, the combination of an upper formed from two strips of fabric 1, a fabric sole 9 sewed to the aforesaid upper, a light and flexible leather sole 2 formed 65 from a single blank and sewed to the upper, having cut out ends 3 and 5, a line of stitching securing the respective edges of said cut out ends together, and leather reinforcing strips 6, 7, and 8 sewed to the fabric upper, 70 substantially as shown.

ABRAHAM LIEBEN.
